CYLINDRICAL BUILDING

Guy Dessauges, 2224 Puntacherstrasse,
Stafa, Zurich, Switzerland

Filed Oct. 4, 1965, Ser. No. 87,315

Term of patent 14 years

(Cl. D13—1)

FIG. 1.

FIG. 2.

FIG. 3.

FIGURE 1 is a front perspective view of a cylindrical building showing my new design;

FIGURE 2 is a side view of the building shown in FIGURE 1;

FIGURE 3 is a perspective view of the building shown in FIGURE 1 as viewed in the direction at right angles to the front side of the building, according to the arrow in FIGURE 2.

The rear of the building not shown in FIG. 1 is plain and unornamented.

I claim:

The ornamental design for a cylindrical building, substantially as shown and described.
